UNITED STATES PATENT OFFICE.

FRED HERTACH AND FRANCIS G. FAY, OF LYNN, MASSACHUSETTS.

VENTILATOR.

1,202,842.

Specification of Letters Patent. Patented Oct. 31, 1916.

Application filed November 5, 1913. Serial No. 799,315.

To all whom it may concern:

Be it known that we, FRED HERTACH and FRANCIS G. FAY, both citizens of the United States, and residents of Lynn, county of Essex, State of Massachusetts, have invented an Improvement in Ventilators, of which the following description, in connection with the accompanying drawings, is a specification, like letters on the drawings representing like parts.

10 The present invention is an improved type of revolving ventilator, having a novel form of means to stimulate the draft or current of air upwardly through and outwardly of the ventilator, also acting to effectually prevent the accumulation of dead air, smoke, or the like, in any part of the ventilator.

15 It is also an object of the present invention to provide a revolving ventilator which will be strong and durable in construction, economical to manufacture, and simple in its construction and operation.

20 In the construction of revolving ventilators or chimney cowls as heretofore made, great difficulty has been experienced in providing a cowl which will stimulate the draft up through the chimney to which the ventilator is attached, as well as through the ventilator itself, many efforts along this line having been heretofore made. The ordinary chimney cowl or revolving ventilator creates an eddy directly in the open mouth of the ventilator, as well as in the top or 25 roof of the ventilator itself, thereby tending to choke up the chimney and to depress the upward tendency of the draft, air current, smoke, etc. Attempts to overcome this difficulty have been made by cutting openings in and through the side walls of the cowl, providing tubes, funnel shaped members and the like, within the cowl, but all such devices have been unsatisfactory.

30 Many openings in the ventilator created increased eddies, while tubes, funnel shaped members, etc., within or through a part of the interior of the cowl tended to create a greater increased area of dead air space than when such funnels were omitted, and thereby tended to clog the draft instead of increasing the same. We have discovered that by providing an opening or openings, preferably two, near the top portion of a chimney cowl of special design, preferably one 35 having a closed pointed end, then forming "air congestors" on the outside of the cowl

to register with said openings, all dead air, smoke, and the like is effectually eliminated and the draft or current of air is increased and stimulated upwardly through the chimney and outwardly through the entire area of the ventilator.

40 Other features of the invention, details of construction and novel combinations of parts, will be hereinafter more fully pointed out and claimed.

45 Referring to the drawings, illustrating a preferred embodiment of the invention, Figure 1 is a side view of our improved ventilator; Fig. 2 is a rear view, looking from the left of Fig. 1; and Fig. 3 is a front view of the ventilator, looking from the right, viewing Fig. 1.

50 Our improved type of ventilator is preferably of a form having a closed and pointed portion held against the direction of the wind, although the novel features may be employed in other types of ventilators, as will be readily understood. A fixed pipe section 1 is adapted to fit on the top of any 55 pipe or chimney to which the ventilator is to be attached, this section 1 being held rigidly on the pipe or chimney, and is arranged to support rotatably the revolving portion of the ventilator, comprising a lower 60 pipe portion 2 and the main upper funnel shaped section 3, having one end 4 closed or pointed against the direction from which the wind will strike the ventilator, and its other flaring end portion 5 open. Around 65 the flaring open portion may be affixed an end guide 6 of wellknown type, by means of short double angle irons 7 and 8, suitably bolted to the exterior of the portion 3 and the inner side of the guide 6. A vane 9 is 70 also affixed to the ventilator, and to the guide 6, as indicated at 10, being also preferably braced by iron straps 11 and 12, as clearly shown in the drawings.

75 In the lower portion 1, we secure at right angles to each other and at a substantial distance above and below each other, the cross rods 13 and 14, each having shoulders 15, bearing against the inner portions of the pipe section 1 and caps 16 threaded thereon and bearing upon the outer surface of the pipe 1, thus firmly uniting the cross bars to this pipe. Each cross bar carries a pipe union 17, preferably each cross bar 13 and 14 comprising two short lengths threaded 80 into the respective sides of the pipe union 17 as illustrated in the drawings. These

two unions 17 afford a bearing for the central stem 18 stepped therein, and extending upwardly through the center of the pipe 1 and the section 2, to a pivotal bearing 19 at 5 the uppermost portion of the section 3. A second bearing for the revolving portion of the ventilator is provided by a cross bar 20, having a union 21 through which the pipe 18 bears, and which cross bar comprises two 10 sections threaded into the union 21 and secured to the sides of the pipe portion 2 by shoulders 22 and threaded caps 23 thereon in a manner similar to that described in connection with the cross bars 13 and 14. This 15 construction affords a simple, cheap, and very strong pivotal support for the revolving portion of the cowl or ventilator. A small cotter pin 24, passing through the stem 18 and resting on top of one of the 20 unions 17 keeps the same in assembled position.

In the conical portion 3 of the ventilator, we provide openings 25 and 26 approximately equi-distant from the pivot 19 and 25 preferably being slightly triangular in form. We may also increase the triangular section by depressing the walls 27 and 28 in the conical portion 3, as shown in Figs. 2 and 3. To the outer surface of the conical 30 portion 3, we affix funnel shaped members 29 and 30, adapted to register with the openings 25 and 26 respectively. These funnel shaped members we term "air congestors", as the opposite ends of each of 35 these air congestors are preferably much larger than the openings 25 or 26 through the conical member 3 with which the respective members 29 and 30 register. These congestors are in fact opening toward the 40 direction from which the wind is blowing, and increasing the velocity of the wind by congesting the area through which it must pass to deliver an increased current through the openings 25 and 26. As these openings 45 are near the top of the member 3, the increased volume of air thus delivered will create a draft upwardly and outwardly through the flaring opening 5 in the ventilator and thereby initiate and stimulate a 50 draft upwardly through the pipe portions 1 and 2 and outwardly through the ventilator. This construction also effectually prevents any eddying of air currents around the sides of the revolving portion of the 55 ventilator, and into the opening 5, but instead creates a draft directly out through the upper portion of the ventilator. These air congestors also act to prevent any accumulation of smoke, in the ventilator, but 60 serve to clear out the same by the initiation of the upwardly and outwardly draft. By having the air congestors 29 and 30 on the

exterior of the ventilator, the interior is left without any devices which would tend to create an eddy or facilitate the accumulation of dead air, smoke and the like, which latter are very objectionable as tending to deaden the draft, as already explained. While we may provide a plurality of such air congestors and openings, we find that 70 the best results have been obtained with the use of two, one at either side of the pivot, thus permitting the main draft or current of air to pass upwardly through the ventilator between the two air congestors, which 75 latter have the effect of stimulating such current, as well as the tendency to create a draft in the proper direction upwardly and outwardly through the uppermost portions of the ventilator. These air congestors 29 80 and 30 may be of any funnel shaped form, but are preferably made as attachments to the conical member 3, utilizing the inclination of the latter for the congesting effect, the sides forming the congestor being but 85 slightly flaring. This construction simplifies the manufacture and renders an economical product possible. In practice, the air congestors 29 and 30 may be cut out of sheet material, bent to substantially proper 90 form, and provided with flanges 32 and 33, which will rest along the outer side of the conical member 3 and may be secured thereto by a series of bolts 34.

Having described our invention, what we 95 claim as new and desire to secure by Letters Patent is:

An apparatus of the kind described, comprising a rotatable ventilator, having a horizontally disposed pyramidal form, pivotal supporting means therefor, spaced apart triangular openings in the upper walls of said horizontally disposed portion and at either side of the pivotal supporting means in substantially balanced relation 105 thereto, and a pair of circular funnel shaped air conductors on the outside of said horizontally disposed pyramidal portion opening toward the pyramidal point and converging to and registering with one of each 110 of said triangular openings respectively, whereby a balanced air resisting construction on the exterior and a substantially smooth non-eddyng construction on the interior of the ventilator is provided.

In testimony whereof, we have signed our names to this specification, in the presence of two subscribing witnesses.

FRED HERTACH.
FRANCIS G. FAY.
